PROJECTOR HEAD BRACKET

Harold G. FitzGerald, Los Angeles, Calif., assignor to
Victorlite Industries, Inc., Los Angeles, Calif., a cor-
poration of California

Application June 6, 1955, Serial No. 36,374

Term of patent 14 years

(Cl. D61—1)

Fig. 1 is a perspective view of the projector head bracket illustrating my new design;

Fig. 2 is a side elevational view of the bracket;

Fig. 3 is a top plan view of the bracket;

Fig. 4 is a view taken from one end of the bracket; and Fig. 5 is a view taken from the other end of the bracket.

The dotted line showing of a projector head and support in Fig. 1 is for illustrative purposes only.

I claim:

The ornamental design for a projector head bracket, as shown and described.
